SOUND PRODUCING DEVICE

Rudolph C. Kucera, Alhambra, Calif.

Application January 14, 1946, Serial No. 641,122

7 Claims. (Cl. 46—191)

1

My present invention has to do with sound producing apparatus and finds its chief application as a noise producer for toy guns, pistols and the like.

It is an object of my invention to provide a sound producing element of this character which is extremely economical of construction, efficient in operation, is easy to install and which is very simple to operate.

Another object is the provision of a sound producing element which may be repeatedly operated without manual resetting.

Still further objects and corresponding advantages will appear from the following description of a presently preferred embodiment of the invention, for which purpose I shall refer to the accompanying drawings, in which:

Fig. 1 is a sectional view showing some parts in elevation, the device being shown in inoperative position;

Fig. 2 is a view similar to Fig. 1 but showing the parts in another position;

Fig. 3 is a section on line 3—3 of Fig. 1;

Fig. 4 is a fragmentary section taken on line 4—4 of Fig. 1;

Fig. 5 is a fragmentary section showing a modified form of apparatus;

Fig. 6 is a section taken on line 6—6 of Fig. 5; and

Fig. 7 is a section similar to Fig. 6 but showing a further modification.

Referring now to the drawings, I show generally at 5 a body which may typify any element in which sound is to be produced and is here used to denote, for instance, the body portion of a toy pistol having a barrel portion 6, a sound chamber 7 and a passageway 8 for part of the sound producing element.

The sound generating element here shown consists of two flat parallel resilient strips 10, 11, secured in normal contacting relationship by having only their left-hand end portions 10a, 11a secured to body portion 5a as by means of a top plate 12 and a screw 15. The right-hand ends of the strips are thus suspended in the sound chamber 7, the right-hand end of the top strip 10 projecting outwardly beyond the contiguous end of strip 11 for the purpose to be described.

Thus to create a sound, the strips are separated and suddenly released and, by virtue of their resiliency, quickly snap together, creating a sound in chamber 7. The sound generating element just described is more or less conventional in the well-known "clapper" type of noise producing devices. It will be understood, of course, that the

2

lower strip 11 may be any hard base element or body capable of creating a sound when struck by top element 10.

It is to the mechanism for actuating the sound generating elements—that is, for flexing the free end of strip 10 away from strip 11 and suddenly releasing it—that my invention is more particularly directed, as will now be described.

Slidably mounted in the passageway 8 between side walls 20, 21 and against side wall 22, I provide a traveling block 25 which has a rounded top end 26 and a front projection 27 providing an upwardly facing shoulder 28, the projection having a somewhat rounded undersurface 29 to permit it to ride over the strip 10 during downward movement of the traveling block.

The traveling block is urged against wall 22 by means of a spring 30 anchored at one end in the body and bearing at its other end in an outwardly flaring recess 31 in the traveling block 25, so that the latter block may slide along wall 22 and swing away from said wall, but is at all times yieldably urged towards said wall.

The means for sliding the block upwardly consists of a trigger or lever 34 in the nature of a bell crank, having a finger-gripping portion 35 depending below the body, and an arm 37, the trigger being secured on a spindle 38 pivoted at its ends in end recesses in set screws 38a threaded in the body. In inoperative or idle position the arm 37 abuts a stop pin 39 mounted transversely of chamber 20. Trigger arm 37 has an opening 40 through its outer end through which a depending extension 42 of the block 25 extends, the extension being headed at 44.

When in inoperative or idle position (Fig. 1) the shoulder 28 of the traveling block rests immediately under the projecting end of the top strip 10. As the trigger arm 37 is swung to the right about its pivot, arm 37 swings upwardly, pushing the traveling block upwardly until the top strip 10 is swung upwardly sufficiently that said end will ride over the shoulder 28. In Fig. 2 the device is shown immediately approaching the latter position. As the strip 10 is thus suddenly released from the shoulder, it springs back by virtue of its own resiliency, striking the strip 11 to create a snapping sound.

To return the traveling block to its inoperative or idle position, I provide a second spring 50, bearing at one end against the body and bearing downwardly at its other end against trigger arm 37. This spring moves the arm 37 downwardly, pulling the traveling block downwardly, while the spring 30 yields sufficiently to enable the projec-

tion 27 to pass downwardly over the contiguous end of strip 10 to cause the device to be reset for a repeat operation.

In Figs. 5 and 6 the elements are as before described, and are given like reference numerals, except in the following respects: in lieu of springs 30, 50 for moving block 25, I here provide a pair of coil springs 55, each looped at its top end about a cross pin 56 carried by the block 25 and looped at its bottom end about stop pin 39. The springs are disposed downwardly and forwardly so as to urge the traveling bar downwardly and forwardly. Here, since the springs constantly urge the bar 25 downwardly against lever arm 37, I merely provide a slot 57 in the bottom end of bar 25 into which slot fits the reduced end 58 of arm 37. I here also show a cam member 60 disposed transversely of chamber 7 in the path of axial movement of the bar 25. This cam is engaged by the rounded end portion 26a of the bar after predetermined upward movement of the bar, and thus the top end of the bar is cammed laterally away from the end of strip 10 to disengage the shoulder 28 from the strip and thereby release the strip. In Fig. 7 the parts are as before described except that here I only utilize one spring 65 instead of the two springs 55, one end of the spring being secured to the block 25 and the other end secured to the stop pin 39.

While, in the foregoing, I have resorted to considerable detail of structure and association of parts in describing a particular example of my invention, I wish it to be understood that I have done so merely to make my invention understood and that I do not limit my invention to such details. On the contrary, my invention is only to be limited as appears in the appended claims.

I claim:

1. In sound producing apparatus, a vibratory element, means for actuating said element comprising a body, a traveling bar mounted in the body for axial sliding movement into and out of operative engagement with said element and for lateral movement towards and away from said element, lever means carried by the body and cooperable with the bar to move the latter axially into operative engagement with said element, and spring means for moving said bar laterally and axially in the opposite direction.

2. Sound producing apparatus comprising a body providing a sound chamber and a passageway opening into the chamber, a pair of sound producing strips disposed in superimposed relationship in the chamber, means securing contiguous ends of the strips to the body, the opposite free ends of the strips being unsecured to the body, the topmost of the strips being resilient whereby, when flexed away from the other strip and released, to engage the latter strip in a sound producing manner, means for so flexing and releasing said topmost strip, including a traveling bar slidably mounted in the passageway and having a lateral projection engageable with the free end of the topmost strip, said projection being releasable from said strip in response to predetermined sliding movement of the bar, and means for sliding the bar.

3. Sound producing apparatus comprising a body providing a sound chamber and a passageway opening into the chamber, a pair of sound producing strips disposed in superimposed relationship in the chamber, means securing contiguous ends of the strips to the body, the oppo-

site free ends of the strips being unsecured to the body, the topmost of the strips being resilient whereby, when flexed away from the other strip and released, to engage the latter strip in a sound producing manner, means for so flexing and releasing said topmost strip, including a traveling bar slidably mounted in the passageway and having a lateral projection engageable with the free end of the topmost strip, said projection being releasable from said strip in response to predetermined sliding movement of the bar, and means for sliding the bar, said last-named means comprising a lever pivotally mounted in the body for operative engagement with the bar, and spring means urging the bar laterally towards the free end of the topmost strip.

4. Sound producing apparatus comprising a body, a pair of superimposed resilient clapper strips secured at one end in the body and having their opposite free ends suspended in the body with the free end of one of the strips projecting beyond the contiguous end of the other strip, a traveling bar loosely mounted in the body for axial movement and for swinging movement towards and away from said projecting end of said strip, spring means opposing swinging movement of the bar in a direction away from said projecting end of said strip, said bar having a lateral projection normally engaging under said projecting end of said strip whereby upon axial movement of the bar in one direction to flex said strip and to release the same after predetermined axial movement of the bar, and means for axially moving said bar.

5. In sound producing apparatus having a flexible strip secured at one end to a base in a manner to produce sound when flexed at one end away from the base and then released to strike thereagainst, a strip flexing and releasing device comprising a body providing a passageway, a slide bar mounted to move axially and laterally in said passageway, said bar having a shoulder portion engageable with the free end of said strip and releasable therefrom in response to predetermined axial movement of the bar, lever means for so axially moving said bar, cam means carried by the body in the path of axial movement of the bar and being engageable with the end thereof to cam the bar laterally and thereby to release said shoulder from said strip, and spring means opposing such lateral movement and for axially moving the bar in the opposite direction.

6. In sound producing apparatus having a flexible strip secured at one end to a base in a manner to produce sound when flexed at one end away from the base and then released to strike thereagainst, a strip flexing and releasing device comprising a body providing a passageway, a slide bar mounted to move axially and swingably in said passageway, said bar having a shoulder portion engageable with the free end of said strip and releasable therefrom in response to predetermined axial movement of the bar, lever means for so axially moving said bar, said bar being laterally swingable away from said strip in response to release of the shoulder from the strip, means for axially moving the bar in the opposite direction, and means pivotally mounting the lever means in the body including a pointed-ended spindle on which the lever is mounted and opposed screws threaded transversely in the body, said screws having recessed inner ends, the pointed ends of the spindle pivotally engaging in said respective recessed ends of the screws.

7. In sound producing apparatus, a body, a

resilient sound strip secured at one end in the body, a bar mounted in the body to slide axially into engagement with the free end of the strip and to move laterally out of engagement with said end of the strip after predetermined flexure of the strip, a trigger in the body operatively engaging the bar to move it axially into engagement with the strip, and cam means in the body in the path of axial movement of the bar and operating to cam the bar laterally to disengage it from said strip. 10
